FOLDABLE BED FRAME

Henry Margiloff, Laurelton, N. Y., assignor to The
Englander Company, Inc., Chicago, Ill., a cor-
poration of Delaware

Application March 2, 1946, Serial No. 651,490

6 Claims. (Cl. 5—152)

1

This invention relates to foldable bed frames and the same has particular reference to a bed frame formed of a plurality of sections hingedly connected for swinging movement thereof to dispose the same in a collapsed compact formation so as to take up a minimum of space for storage and shipment and which when disposed in collapsed relation is secured against accidental or unintentional swinging movement of the sections into bed forming relation.

The invention also has in view a bed frame of the indicated character which includes similar opposite end sections and a collapsible intermediate section hingedly connected to the end sections for movement from an aligned bed forming relation to a collapsed condition supported upon the intermediate section with the opposite end sections disposed in spaced parallel relation extending upwardly from the opposite ends of the intermediate section and adapted to receive and retain the mattress therebetween in folded relation.

The invention further has for an object the provision of an intermediate section of cross-legged construction which is collapsible by the spreading apart of the lower ends of the legs from a position in which the intermediate section is disposed in longitudinal alignment with the end sections to a relatively lower position with the end sections extending upwardly therefrom and locked in spaced apart parallel relation by the collapsing movement of the cross-legs.

The invention also comprehends the provision of cross-legs having wheels for supporting the frame thereon when in collapsed relation for facilitating rolling or movement of the frame over the supporting surface and which wheels are disposed out of contact with the supporting surface when the frame is arranged in bed forming relation with the low ends of the cross-legs supporting the intermediate section.

With the foregoing and other objects in view, reference is now made to the following specification and accompanying drawings in which the preferred embodiment of the invention is illustrated.

In the drawings:

Fig. 1 is a side view of a bed frame constructed in accordance with the invention and illustrating the same in bed forming relation.

Fig. 2 is a top plan view thereof with parts broken away to illustrate the underlying construction.

Fig. 3 is an enlarged side view thereof with the same shown in partially collapsed formation.

2

Fig. 4 is a similar view showing the same in fully collapsed condition.

Fig. 5 is a transverse vertical sectional view taken approximately on line 5—5 of Fig. 2.

5 Fig. 6 is a fragmentary longitudinal sectional view taken approximately on line 6—6 of Fig. 2. Referring to the drawings by characters of reference the bed frame consists of similar opposite end sections A and B and an intermediate section C located between the end sections and arranged in horizontal alignment therewith when disposed in bed forming relation.

The end sections A and B each comprises spaced parallel side rails 10 and an end rail 11 connected between the side rails 10 at the outer ends thereof and which rails are of angle iron construction arranged with the horizontal flanges 12 disposed uppermost and the vertical flanges 13 disposed outwardly. The end sections A and B are each provided with a tubular upwardly extending U-shaped head 14 secured to the horizontal flange 12 of the end rail 11 thereof. A pair of leg members 15 are also provided for each section A and B which leg members are of angle iron construction and are arranged with the side flanges 16 thereof located outermost and pivoted at their upper ends against the inner faces of the vertical flanges 13 of the side rails 10 on pivot pins 17 and with the transversely disposed flanges thereof located rearwardly.

20 The intermediate section C includes spaced parallel side rails 18 which are formed with downwardly directed terminals 19 at the opposite ends thereof. The side rails 18 and terminals 19 are of angle iron construction and are arranged with the horizontal flange 20 of the side rails 18 disposed uppermost and in horizontal alignment with the horizontal flanges 12 of the side rails 10 of the end sections A and B. The flanges 20 are curved downwardly at the ends of the side rails 18 and are located outwardly at the opposite ends of the section in the terminal ends 19 thereof with the side flanges 21 of said side rails being located laterally outward. The horizontal flanges 12 of the side rails 10 of the end sections A and B are cut away as at 22 with the vertical flanges 13 thereof protruding inwardly beyond the inner ends of the flanges 12 with the inwardly projecting portions of the flanges 13 disposed against the outer face of the vertical flanges of the side rails 18 of the intermediate section C and pivoted thereto on pivots 23. Link members 24 consisting of flat bars having curved inner ends are pivoted against

the inner faces of the side flanges 21 of the terminal ends 19 of each of the side rails 18 of the intermediate sections C on pivots 25 with the outer ends of said links pivoted against the inner faces of the side flanges 16 of the leg members 15 on pivots 26 adjacent the pivotal connection 17 of the leg members with the sections A and B respectively for effecting swinging movement of the leg members 15 from right angular relation with the end sections for supporting the same when disposed in bed forming relation to a retracted condition extending longitudinally of and in nested relation between the flanges 12 and 13 of the side rails 18 when the sections are swung into collapsed formation.

The intermediate section C also includes a collapsible support consisting of a pair of pivotally connected crossed-legs. The crossed-legs are of general U-shaped formation consisting of side legs 27 and 28 at each side of the section, corresponding legs being connected together at their lower ends by a transversely extending bight portion 29. The side legs 27 and 28 are pivoted together by pivots 30 intermediate their ends with the opposite ends thereof located outwardly of the side flanges 21 of the intermediate section C and connected by pins 31 to brackets 32 disposed against the inner faces of said flanges which pins extend through and are slidable in elongated slots 33 formed in said flanges 21. The brackets 32 are connected by a coiled contractile spring 34 for resiliently maintaining the upper ends of the pivotally connected legs 27 and 28 in inward relation adjacent the inner ends of the said slots and tensioning the outer ends of the legs 27 and 28 against expansion thereof away from each other.

A pair of links 35 of longitudinal arcuate formation are provided for each of the end sections A and B which links are pivoted at their outer ends on pivot pins 36 to the outer faces of the flanges 13 of the side rails 18 adjacent the pivotal connection of the same with the intermediate section C. The other ends of the links 35 connected to the end section A are pivoted to the inner ends of the legs 27 while the links 35 connected to the end sections B have their other ends pivoted to the inner ends of the legs 28 of said cross-legs. This construction effects a collapsing or spreading apart of the lower ends of the cross-legs when the end sections A and B are swung from horizontal alignment with the intermediate section C to a collapsed relation in which the end sections extend upwardly therefrom in parallel spaced relation to dispose the side rails 18 of the intermediate section at a relatively lower elevation whereby the bed frame takes up a minimum of space for storage and shipment when in collapsed condition.

The lower ends of the cross-legs 27 and 28 have angulated portions 38 which are disposed in parallel vertical relation when the sections are in bed forming relation, the said portions 38 being connected by the bight portion 29 which has its central portion 39 vertically offset to thereby provide U-shaped bases 40 for engagement with a supporting surface at each side for supporting the intermediate section C. Secured to the elevated portion 39 of the bight portion 29 of each of the cross-legs 27 and 28 are outwardly and downwardly projecting apertured lugs 41 in which are pivotally mounted caster rollers 42 disposed at an angle to the bases 40 and angulated portions 38 of the cross-legs 27 and 28. The arrangement is such that when the lower ends of

the cross-legs are swung outwardly by the collapsing or upward swinging movement of the end sections to dispose the bed frame in collapsed formation the bases 40 are swung to angular relation and the casters 42 are arranged in vertical formation for engagement with the supporting surface whereby the bed frame may be readily rolled or moved over the supporting surface when in collapsed condition.

The intermediate section C also includes transversely extending angle bars 43 secured at their opposite ends to the lower ends of the terminals 19 of the side rails 18 thereof to thereby rigidly connect the opposite side rails together and hold the same in lateral spaced relation.

A wire spring 44 is connected with and stretched between the side rails 12 and the end rails 11 of the opposite end sections and between the side rails 18 of the intermediate section for supporting a mattress thereon and which together with the mattress is adapted to be folded and unfolded with the frame sections. The angle bars 43 are located a sufficient distance below the wire spring 44 to provide a clearance therebetween so that when the weight of the mattress and a person lying thereon is imposed upon the spring the same does not contact with the said angle bars.

When the bed frame is disposed in collapsed formation by the upward swinging of the end frames and the downward collapsing of the intermediate section, the pivotal connections 26 of the links 24 with the leg members 15 are swung to a position over top dead center of the pivotal connection 25 of the inner ends of the links 24 with the terminals 19 whereby the end sections are retained in collapsed formation against accidental or unintentional swinging thereof into bed forming relation. Furthermore, the said end sections are retained in said collapsed formation by the weight thereof upon the intermediate section which is elevated by the outward swinging of the end sections. When in collapsed formation the caster rollers 42 engage with the supporting surface so as to permit of the rolling movement of the bed frame thereover. The bases 40 of the cross-legs 27 and 28 are then out of engagement with the supporting surface. When, however, the bed frame is disposed in bed forming relation the caster rollers 42 are out of engagement with the supporting surface and the bases 40 support the intermediate section C.

What is claimed is:

1. In a collapsible bed frame, similar end sections each including opposite side rails, an end rail connected with the side rails at the outer end thereof and a leg member pivoted to each of the side rails, an intermediate section including opposite side rails pivotally connected at their opposite ends to the inner ends of the side rails of the end sections and having downwardly directed terminals at the opposite ends thereof, links having curved inner ends pivoted to the lower ends of said terminals and at the outer ends to the leg members, cross-legs pivotally connected together intermediate their ends and having their upper ends connected with the side rails of the intermediate section for limited sliding movement thereof from a position supporting the intermediate section in aligned bed forming relation with the end sections to a collapsed relation with the intermediate section arranged at a relatively lower position, links pivotally connected to the cross-legs adjacent the upper ends thereof and to the side rails of the end sections

adjacent their inner ends for effecting collapsing movement of the intermediate section by the upward swinging of the end sections from bed forming relation to a folded upwardly extending formation with the end sections supported by the intermediate section in spaced parallel relation and the leg members swung into adjacent relation with the side rails of the end sections, a transversely extending portion connecting the lower ends of the cross-legs on one side of the frame with the cross-legs respectively on the opposite side thereof, said transversely extending portion being elevated centrally providing bases at the opposite ends thereof for supporting the intermediate section when in bed forming relation and rollable members swivelly connected to said transversely extending portions in angular relation therewith for rollably supporting the bed frame when disposed in collapsed relation.

2. In a collapsible bed frame, similar end frame sections having leg members pivoted to the opposite sides thereof, an intermediate frame section pivoted to the end sections and having downwardly directed terminals at the opposite ends thereof, links pivoted to the lower ends of said terminals and to the leg members, cross-legs pivotally connected together intermediate their ends and each cross-leg being connected with said intermediate section for limited sliding movement thereof for movement of the cross-legs from a position supporting the intermediate section in aligned bed forming relation with the end sections to a collapsed relation with the intermediate section arranged at a relatively lower position and crossed links pivotally connecting the cross-legs and the opposite sides of the end sections for effecting collapsing movement of the intermediate section by the upward swinging of the end sections from bed forming relation to a folded upwardly extending formation with the end sections supported by the intermediate section and extending upwardly therefrom in spaced parallel relation and the leg members swung to nested relation with the opposite sides of the end sections.

3. In a collapsible bed frame, similar end frame sections having leg members pivoted to the opposite sides thereof, an intermediate frame section pivoted to the end sections, links pivoted to said intermediate frame section and to the leg members, cross-legs pivotally connected together intermediate their ends and each cross-leg being connected with said intermediate section for limited sliding movement thereof for movement of the cross-legs from a position supporting the intermediate section in aligned bed forming relation with the end sections to a collapsed relation with the intermediate section arranged at a relatively lower position and links crossing each other and pivotally connecting the cross-legs and the opposite sides of the end sections for effecting collapsing movement of the intermediate section by the upward swinging of the end sections from bed forming relation to a folded upwardly extending formation with the end sections supported by the intermediate section in spaced parallel relation and the leg members swung to nested relation with the opposite sides of the end sections, and rollable members swivelly connected to said cross-legs and arranged with the swivel axes thereof disposed in angular relation to the cross-legs respectively for rollably supporting the bed frame when disposed in folded relation and being moved out of engagement with the supporting

surface when the sections are in bed forming relation.

4. In a collapsible bed frame, similar end sections each including opposite side rails, an end rail connected with the side rails at the outer end thereof and a leg member pivoted to each of the side rails, an intermediate section including opposite side rails pivotally connected at their opposite ends to the inner ends of the side rails of the end sections and having downwardly directed terminals at the opposite ends thereof, links pivoted to the lower ends of said terminals and at the outer ends to the leg members, cross-legs pivotally connected together intermediate their ends and having their upper ends connected with the side rails of the intermediate section for limited sliding movement thereof from a position supporting the intermediate section in aligned bed forming relation with the end sections to a collapsed relation with the intermediate section arranged at a relatively lower position and links pivotally connected to the cross-legs adjacent the upper ends thereof and to the side rails of the end sections adjacent their inner ends for effecting collapsing movement of the intermediate section by the upward swinging of the end sections from bed forming relation to a folded upwardly extending formation with the end sections supported by the intermediate section in spaced parallel relation and the leg members swung into adjacent relation with the side rails of the end sections.

5. In a collapsible bed frame, similar end sections each having leg members pivotally connected to the opposite sides thereof, an intermediate frame section pivoted to the end sections, cross-legs located on each side of the frame, said cross-legs being pivotally connected together intermediate their ends and each leg thereof being connected with said intermediate section for limited sliding movement thereof for movement of the cross-legs from a position supporting the intermediate section in aligned bed forming relation with the end sections to a collapsed relation with the intermediate section arranged at a relatively lower position, link members pivotally connecting the cross-legs and the end sections for effecting collapsing movement of the end sections by the upward swinging of the end sections from bed forming relation to a folded upwardly extending formation with the end sections supported by the intermediate section in spaced parallel relation, said cross-legs having transversely extending portions connecting the opposite legs together providing a support when the sections are in bed forming relation, and rollable members connected to said transversely extending portions in angular relation to the horizontal when the sections are in bed forming relation and in upright relation when the sections are in folded relation for rollably supporting the bed frame when disposed in folded relation.

6. In a collapsible bed frame, end frame sections having leg members pivoted to the opposite sides thereof, an intermediate frame section pivoted to the end sections, pivotally interconnected crossed legs connected with the intermediate section for limited movement relative thereto and for movement of the intermediate section from bed forming relation with the end sections to a collapsed relation with the intermediate section arranged at a lower level and the end section disposed in upwardly extending relation, links connected to the upper ends

of the crossed legs and to said end sections respectively for collapsing the crossed legs to lowered relation for lowering the intermediate frame section with the swinging of the end sections to said upwardly extending relation, said crossed legs being adapted to engage a supporting surface to support said intermediate frame section when in bed forming relation, and said crossed legs having rollable members connected thereto in angularly disposed relation and adapted to engage the supporting surface for rollably supporting the bed frame when in collapsed relation and for movement thereof out of engagement with the supporting surface with the movement of the sections to bed forming relation.
